NELS BONGOM, OF LAKE MILLS, IOWA.

TICKET-PRINTING DEVICE.

1,401,955.

Specification of Letters Patent.

Patented Jan. 3, 1922.

Application filed March 3, 1921. Serial No. 449,552.

To all whom it may concern:

Be it known that I, NELS BONGOM, a subject of the King of Norway, and a resident of Lake Mills, in the county of Winnebago and State of Iowa, have invented a new and useful Improvement in Ticket-Printing Devices, of which the following is a full, clear, and exact description.

My invention relates to improvements in ticket printing devices and it consists in the combinations, constructions and arrangements herein described and claimed.

An object of my invention is to provide a device having means for printing characters, such as numerals, upon a ticket strip so that the portions of the ticket strip successively printed can be torn off when printed and used as desired.

A further object of my invention is to provide a device of the type described having a casing provided with a movable slide that normally covers the end portion of the ticket strip and is operable to permit the end portion of the ticket strip to be grasped after it has been printed so that the same can be extended and torn off.

A further object of my invention is to provide a device of the type described that has a plurality of relatively movable type-holding disks which can be arranged to permit the printing of various values on the ticket strip.

A further object of my invention is to provide a device of the type described that has a plurality of relatively arranged type-holding disks and yieldable means for maintaining such disks in adjusted positions.

A further object of my invention is to provide a device of the type described that is relatively simple in construction and operation, compact in form, and not likely to get out of order easily.

A further object of my invention is to provide a device of the type described that is effective for the purpose intended and thoroughly practical commercially.

Other objects and advantages will appear in the following specification, and the novel features of the invention will be particularly pointed out in the appended claims.

My invention is illustrated in the accompanying drawings, forming part of this application, in which,

Figures 1, 2, and 3 are, respectively, a side

elevation, a plan view, and an end view of 55 the device,

Figure 4 is a section along the line 4—4 of Figure 3, and,

Figure 5 is a section along the line 5—5 of Figure 1. 60

In carrying out my invention, I provide a casing 1 that is made of any suitable material, preferably a light stamping, and has the form shown in the drawings. The casing 1 is open at one side to permit access to 65 the interior thereof and a closure 2 for this open side is hinged at 3—3 to the lower wall of the casing and is normally maintained in closed position in any suitable manner, as by means of a spring lug extension 4 that is 70 adapted to frictionally engage with the contiguous portion of the upper wall of the casing.

Rotatably mounted on a stub shaft 5 that is secured to the fixed side wall of the casing 75 1 and projects within the interior thereof at a spaced distance from the rear end wall of the casing is a roll 6 consisting of the convolutions of a single paper ribbon or ticket strip 7. A spring 8 having one end secured 80 at 9 to the lower wall of the casing 1 is arranged to bear against the outer convolution of the roll 6 and yieldingly permits the rotation of the roll as the paper ribbon is unwound therefrom. 85

An arbor 10 is formed with a flange 11 and the latter is secured to the fixed side wall of the casing 1 by rivets 12, or the like, so that the arbor projects within the interior of the casing at a spaced distance from 90 the forward wall thereof and is practically parallel with the stub shaft 5. Rotatably mounted on the arbor 10 is the hub 13 of a type-carrying disk 14. The hub 15 of a second type-carrying disk 16 is rotatably 95 mounted on the hub 13 and a third type-carrying disk 17 is rotatably mounted on the hub 15. A spacing disk or washer 18 is interposed between the adjacent faces of the type-carrying disks 14 and 16 and a similar 100 spacing disk or washer 19 is interposed between the adjacent faces of the type-carrying disks 16 and 17, so that each disk can be rotated freely without frictionally contacting with an adjacent disk. 105

It is to be noted that the peripheries of the three type-carrying disks are alined and on the periphery of each in type (not

shown) is a series of characters, preferably numerals. The hubs 13 and 15 extend toward the closure 2 until the ends thereof are practically flush with the outer face of the type-carrying disk 17. The outer face or side wall of the disk 17 and the corresponding ends of the hubs 15 and 13 are cooperatively curved as shown to receive a key 20 that is intermediately rotatably mounted on a screw 21 having its inner end disposed in a threaded opening in the arbor 10 so that the head thereof is countersunk in a recess 23 in the key 20. The latter projects through an opening 53 in the closure 2. The opening 53 is circular to permit rotation of the key 20 and to disclose to view concentrically arranged series of characters that are marked on the outer ends of the hubs of the disks 14 and 16 and on the outer face of the disk 17, being indicated at 26, 25, and 24, respectively. These characters correspond in number, relative arrangement, and identity with the characters that are carried in type on the peripheries of the several type-carrying disks.

In order to rotate the disks 14, 16, and 17 as required in order to locate the type on the peripheries thereof in desired positions, the outer face of the disk 17 and the outer end walls of the hubs 15 and 13 are each formed with a plurality of teeth, denoted by 27, 28, and 29, respectively, and these teeth are arranged in concentric rings. The key 20 is fashioned with a slot 30 that extends radially with respect to the axis of the disks and communicates with a recess 31 in the inner surface of the key. Disposed within this slot for movement therewith is an adjusting member 32 and intermediately secured, as at 33, to the inner end of the adjusting member is a substantially U-shaped spring locking member 34 having parallel arms 35 and 36 each bent backwardly at its extremity and adapted to enter spaces between adjacent teeth of the series indicated at 27, 28, and 29, so that the key 20 can be locked at will to any one of the type-carrying disks 14, 16, and 17 and the selected disk rotated by rotating the key about its axis.

The disk 14 is formed with an annular recess 37 in its inner side wall and the wall of this recess has therein a plurality of indentations 38, the number and relative arrangement of which corresponds with the number and arrangement of the characters indicated at 26. The disks 16 and 17 are each formed with a plurality of indentations 39 and 40, respectively, in their inner side walls and these indentations likewise correspond in number and relative arrangement with the characters indicated at 25 and 24, respectively. A plate 41 (see Fig. 4), that is secured to the fixed side wall of the casing 1 adjacent to the upper edge thereof overlies the peripheries of the type-carrying disks

and has depending therefrom spaced apart spring arms 42, 43, and 44. The spring arm 42 depends between the inner side of the fixed wall of the casing 1 and the adjacent side of the disk 14, being formed at its extremity to engage with the indentations 38, thereby tending to maintain the disk 14 in adjusted positions. The spring arm 43 depends between the disks 14 and 16 and is formed at its extremity to engage with the indentations 39. The spring arm 44 is arranged for engagement with the indentations 40.

An ink impregnated endless ribbon 45 is loosely mounted on the peripheries of the disks 14, 16, and 17, and passes over the plate 41, as clearly shown in Fig. 4. A platen that preferably has a circular head 46 disposed exteriorly of the upper wall of the casing 1 and a square-sectioned shank or body portion 47 that projects through an opening 48 in the upper wall of the casing and a slot 49 in a slide 50 that underlies the upper wall of the casing is operable to press the end portion of the ticket strip downwardly against the underlying ribbon which in turn is forced against the type positioned therebeneath so that the impression of the latter is printed on the ticket strip. A spring 51 mounted on the shank or body portion 47 between the head 46 and the upper wall of the casing tends to force the platen upwardly while lugs 52 extending laterally from the shank 47 at its lower end engage with the under surface of the slide 50 and limit the movement of the platen upwardly.

The slide 50 at its forward end rests upon a rearwardly turned integral extension 54 to the front wall of the casing 1 and is guided and supported adjacent to its rearward end by guide hanger lugs or bracket members 55 that depend from the upper wall of the casing. The slide 50 is bent downwardly at its rearward end to provide a flange 56 and between this flange and a flange 57 that is formed integrally with the upper wall of the casing is a spring 58 that tends to thrust the slide forwardly so that the forward end thereof is practically flush with the front wall of the casing 1.

From the foregoing description of the various parts of the device, the operation thereof may be readily understood. The arm 35 of the spring locking member 33 is shown in Fig. 5 engaging teeth 29 of the hub of the disk 13. The latter can therefore be rotated by turning the key 20 until a desired character of the series 26 is directly beneath the platen. A like number in type on the periphery of the disk 13 will then be positioned for printing the overlying ticket strip. The arm 35 will disengage the teeth 26 when the adjusting member 32 is moved along the slot 30. The disk 16 can be rotated when the adjusting member has been

5 moved along the slot 30 until the arm 35 engages the teeth 28. A further movement of the adjusting member along the slot 30 will move the arm 36 into engagement with the teeth 27 and the disk 17 can then be rotated. Since the teeth 29, 28, and 27 are arranged in concentric rings, it is only necessary to move the adjusting member 32 along the slot 30 to occasion the locking of the 10 key 20 to any one of the several disks, no matter what the relative positions of the disks may be.

When the desired numerals have been alined beneath the platen, the latter is forced 15 downwardly and the underlying portion of the ticket strip will be printed in the manner hereinbefore described. In practice, the plate 41 will bear type (not shown) indicating the name of the establishment in 20 which the device is used so that this data will appear on each printed portion of the ticket strip. Since the inking ribbon is loosely mounted on the peripheries of the type-carrying disks, it will be moved 25 slightly at each printing operation and the wear on any part thereof will not be excessive.

The slide 50 is enlarged at its forward end to provide a thumb bar or rest 59 so that 30 the device can be conveniently manipulated to move the slide rearwardly in a slot 60 in the upper wall against the tension of the spring 58, thus exposing the end portion of the ticket strip and permitting the same to 35 be grasped and drawn forwardly until the printed portion is extended beyond the front end of the casing 1. The printed portion can then be torn off from the strip when the same is grasped firmly and moved either up- 40 wardly or downwardly as either the slide or the end wall of the casing 1 will serve as a shearing member. The torn off portion is adapted for use for the purposes for which tickets of this type are intended.

45 The device is particularly suitable for use in restaurants, soda fountains, and like places where the amount of a purchase is marked on a ticket which is handed to the customer who pays the amount indicated to a cashier. In each instance, a legible printed record of each transaction is instantly 50 available and the printed amount can be noted for the purpose of recording, or for any other reason, much more quickly than 55 when the only record of the transaction was a penciled notation on a ticket as the penciled notations are sometimes practically illegible. The device is compact and can be carried about in a pocket of a garment. It 60 can be quickly manipulated to print various amounts on the ticket strip.

I claim:

65 1. A device of the character described comprising a casing having an opening in its wall, a roll of ticket strip rotatably sup-

ported within the casing and having the free end of said strip arranged for withdrawal from the casing through said opening, a shaft disposed within said casing, a plurality of disks rotatably mounted on said shaft 70 with their peripheries aligned and underlying the end portion of said ticket strip, each of said disks being provided with a series of characters on its periphery in type, an ink-impregnated ribbon interposed between the 75 peripheries of said disks and the overlying portion of said ticket strip, a key rotatably mounted on said shaft, means carried by said key for selectively engaging said disks, whereby said disks may be turned independently of one another with said key, and means operable at will for forcing the end portions of said ticket strip against the ribbon covered type to occasion the printing of 80 said overlying portion of said ticket strip as 85 required.

2. A device of the character described comprising a casing having a portion of its upper wall cut away adjacent the forward end thereof, the front end wall of the casing 90 being provided with a portion extending rearwardly from the upper edge thereof parallel with the upper wall and in a lower plane, a roll of ticket strip rotatably mounted within the casing and arranged with the 95 free end portion of the strip overlying said extension to the front wall of the casing, and means carried by said casing and having a portion thereof superposed on said end portion of the ticket strip for normally covering 100 the latter, said means being slidable inwardly to expose the end portion of the ticket strip.

3. A device of the character described comprising a casing having a portion of its 105 upper wall cut away adjacent the forward end thereof, the front end wall of the casing being provided with a portion extending rearwardly from the upper edge thereof parallel with the upper wall and in a lower 110 plane, a roll of ticket strip rotatably supported within the casing with the end portion of the strip disposed upon the extension to the front wall of the casing, means carried by said casing contiguous to the end portion of the ticket strip for normally covering the latter, said means being slidable inwardly to expose the end portion of the ticket strip, and spring means engaging with the last named means for returning the latter to normal position.

4. A device of the character described comprising a casing having a portion of its upper wall cut away adjacent the forward end thereof, the front end wall of the casing 125 being provided with a portion extending rearwardly from the upper edge thereof parallel with the upper wall and in a lower plane, a roll of ticket strip rotatably supported within the casing with the end por- 130

tion of the strip disposed upon the extension to the front wall of the casing, a slide having its outer end portion superposed on the end portion of said ticket strip and having 5 its outer end normally flush with the front end of said casing, means for supporting said slide adjacent its inner end for slidable movement toward the rear end of the casing, and means for yieldingly resisting movement of the slide toward the rear end of the casing, whereby the end portion of the ticket strip is normally covered and is exposed 10 when said slide is forced inwardly.

5. A device of the character described 15 comprising a casing having a portion of its upper wall cut away adjacent the forward end thereof, the front end wall of the casing being provided with a portion extending rearwardly from the upper edge thereof parallel with the upper wall and in a lower plane, a roll of ticket strip rotatably disposed upon the extension to the front wall of the casing, means carried by said casing contiguous to the end portion of the ticket 20 strip for normally covering the latter, said 25

means being slidable inwardly to expose the end portion of the ticket strip, and yieldable means engaging with the roll of ticket strip for normally preventing the unwinding of the ticket strip therefrom. 30

6. A device of the character described comprising a casing having a portion of its upper wall cut away adjacent the forward end thereof, the front wall of the casing being provided with a portion extending rearwardly from the upper edge thereof substantially parallel with the upper wall and in a lower plane, a roll of ticket strip rotatably supported within the casing with the end of the ticket strip disposed upon the extension to the front wall of the casing, means carried by said casing contiguous to the end portion of the ticket strip for normally covering the latter, said means being slidable inwardly to expose the end portion of the ticket strip, and means adapted for engagement with the ticket strip adjacent its end and operable at will to occasion the printing of various characters on said ticket strip. 35 40 45

NELS BONGOM.
